CONVEYER MECHANISM FOR FOLDING
CARTON BLANKS

Albert W. Liebl, Philadelphia, Pa., assignor to
Container Corporation of America, Chicago, Ill.,
a corporation of Delaware

Application September 4, 1948, Serial No. 47,868

15 Claims. (Cl. 93—49)

1

This invention relates, generally, to folding means, and it has particular relation to means for folding paperboard blanks that form, when set up, rectangular cartons.

Among the objects of this invention are: To fold sequentially the side walls of a paperboard blank, its front wall and then its back wall; to position a plate in the path of the side walls to hold them folded; to position a finger in the path of the front wall for folding the same backwardly; to mount the finger rockably so that it can be moved out of the way of the leading edge of the bottom wall after the front wall has been folded; to bias the front wall folding finger against such movement; to avoid the necessity for positively synchronizing the conveyor mechanism that moves the blank forwardly with the front and back wall folding mechanism; to move the front and back wall folding mechanism forwardly by force transmitted through the blank; to mount the front and back wall folding mechanism on an endless flexible cable, such as a chain or belts, having a run paralleling the path of the bottom wall of the blank; to secure a lug on the cable to be engaged by the leading edge of the bottom wall of the blank for moving the cable forwardly and also to secure a folding finger on the cable arranged to fold over automatically the back wall of the blank; to mount the lug and folding finger adjustably on the cable to accommodate blanks having bottom walls of various lengths and widths; to employ a plurality of sets of lugs and folding fingers on the cable, one or more sets for each blank; and to provide duplicate endless flexible cables or chains for carrying the sets of lugs and folding fingers in aligned relation.

Other objects of this invention will, in part, be obvious, and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following description taken together with the accompanying drawings, in which:

Figure 1 is a top plan view, somewhat diagrammatic in character, showing a folding means constructed in accordance with this invention;

2

Figure 2 is a view, in side elevation and also somewhat diagrammatic in character, showing additional details of the folding mechanism illustrated in Figure 1;

5 Figures 3 and 4 are detail views illustrating how the front wall of the blank is folded over; and

Figures 5, 6 and 7 are perspective views of the paperboard blank in various stages of the folding of the side, front and rear walls.

Referring now particularly to Figures 5, 6 and 7 of the drawings, it will be observed that the reference character 10 designates, generally, a paperboard blank having a bottom wall or 15 panel 11, side walls or flaps 12 and a front wall or flap 13. As shown in Figure 5, the side walls or flaps 12 have been folded over the bottom wall or panel 11 while the front wall or flap 13 has yet to be folded over along a fold line 20 or leading edge 14 of the bottom wall or panel 11. The blank 10 also includes a back wall or flap 15 which is arranged to be folded along a fold line or trailing edge 16 of the bottom wall or panel 11. It will be understood that the side 25 walls or flaps 12 first are folded as shown in these figures of the drawings. Next the front wall or flap 13 is folded over as indicated in Figure 6 and, finally, the back wall or flap 15 is folded over as indicated in Figure 7. The blank 10, 30 as shown in Figure 7, can be packaged or stored in the folded condition and it is ready to be set up to form a rectangular carton by moving the walls or flaps 12, 13 and 15 into positions at right angles to each other and to the bottom 35 wall or panel 11. Suitable provision is made for interlocking the corners of the carton when it is set up. For present purposes it is unnecessary to show these details since the present invention has to do particularly with the manner 40 in which the walls or flaps 12, 13 and 15 are folded over the bottom wall or panel 11 to provide the folded blank as shown in Figure 7.

In order to fold the blank 10 in the manner just described, the folding mechanism, shown 45 generally at 19 in Figures 1 and 2 of the drawings, may be employed. The folding mechanism 19 may constitute a separate machine or it may form a part of a gluing machine as may be desired. The folding mechanism 19 includes side 50 frame members 20 and 21 the supports for which are not shown in the drawings in order to simplify the disclosure.

The blank 10 is arranged to be moved from the right hand end of the folding mechanism 19 as 55 viewed in Figures 1 and 2 to the left end by means

of conveyor belts. These conveyor belts include a pair of bottom conveyor belts 22 which are trained at the left hand end over pulleys 23. It will be understood that the underside of the bottom wall 11 rests on the two bottom conveyor belts 22 and that it is moved forwardly thereby in conjunction with a pair of top conveyor belts 24. The top conveyor belts 24 are trained over pulleys 25 and 26 at the opposite ends. Also the top conveyor belts 24 are trained over pulleys 27, 28, 29 and 30 which are arranged to direct the top conveyor belts away from the corresponding bottom conveyor belts 22 for a portion of their travel so as to permit the front wall or flap 13 to be folded over the bottom wall or panel 11 in a manner to be described presently. In practice, suitably disposed guide pulleys (not shown) are provided for guiding the belts 24 onto the pulleys 27, as is known. As shown, the top conveyor belts 24 are provided each with a half twist 31 between the pulleys 25 and 27 for the purpose of folding the side walls or flaps 12 over the bottom wall or panel 11. In order to accomplish that, the portions of belts 24 to the right, as viewed in Figure 1, of the half twists 31 thereof, are disposed outward beyond belts 22, as are the pulleys 25, as will be understood from what has been said.

In some cases where the width of the side walls or flaps 12 is relatively great, it may be desirable to provide for holding them in the folded position over the bottom wall or panel 11. For this purpose a plate 34 may be provided. As shown in Figure 2, the plate 34 is inclined or angularly disposed above the path of the blank 10 just after the side walls or flaps 12 have been folded over by the half twisted sections 31 of the top conveyor belts 24. The inclined plate 34 may be omitted where the belts 22 and 24 are of sufficient width so as to hold the side walls or flaps 12 in the folded position.

With a view to folding over the front wall or flap 13, there is provided a front wall folder in the form of an inverted L-shaped finger 35. The front wall folder or L-shaped finger 35 is fast on a shaft 36 which is journaled at its ends in bearings 37 that are carried by the side frame members 20 and 21. As shown in Figure 3, the shaft 36 is provided with an arm 38 to which a coil tension spring 39 is attached. The spring 39 operates through the arm 38 to bias the front wall folder or finger 35 to the position shown in Figure 2 of the drawings. This construction permits the front wall folder or finger 35 to be swung out of the way of the leading edge 14 of the bottom wall or panel 11 as the blank 10 is moved forwardly by the conveyor belts 22 and 24. It will be observed that the front wall folder or finger 35 includes a long arm 40 having a lower curved end 41 which extends downwardly between the pair of bottom conveyor belts 22 and below the path of movement of the bottom wall or panel 11 of the blank 10. The curved lower end 41 is provided to facilitate the engagement of the forward edge of the front wall 13 with the front wall folder or finger 35. The spring 39, as shown in Figure 3, is of sufficient strength to hold the front wall folder or finger 35 in the position there shown and thus causes the front wall or flap 13 to be folded along the fold line or leading edge 14 as the blank 10 is moved forwardly by the conveyor belts 22 and 24. Finally, the forward edge of the front wall or flap 13 engages a short arm 42 of the front wall folder or finger 35 and thus is prevented from moving further relative

to the finger 35. As a result of the continued forward movement of the bottom wall or panel 11 of the blank 10, the finger 35 is swung in a clockwise direction to the position shown in Figure 4. The tension of the spring 39 is sufficient to fold the front wall or flap 13 back over the bottom wall or panel 11 as shown in Figure 4. Also, the front wall folder or finger 35 in this manner is swung out of the path of the blank 10 which continues to move forwardly.

As the blank 10 continues to move forwardly after the front wall or flap 13 has been folded over in the manner just described, the leading edge 14 engages a pair of lugs 45 which may be adjustably mounted on a pair of endless flexible cables or chains 46. It will be observed that the cables or chains 46 are trained over sprockets 47 and 48 and over an idler sprocket 49. The idler sprocket 49, as shown in Figure 2, is carried at the lower end of an adjusting arm 50 which serves to maintain the desired tension in the cables or chains 46. It will be understood that the cables or chains 46 are moved forwardly solely by force transmitted from the conveyor belts 22 and 24 through the blank 10 and its engagement with the lugs 45. In other words the cables or chains 46 are not positively driven in synchronism with the conveyor belts 22 and 24 other than in the manner just described.

The back wall or flap 15 of the blank 10 is folded over as the last step in the processing of the blank 10 through the folding mechanism 19. For this purpose a pair of folding fingers 51 is provided and they are adjustably connected to the cables or chains 46. The reason for the adjustable connection of the folding fingers 51 as well as of the lugs 45 is to permit the same apparatus to be employed with blanks 10 having different lengths of bottom walls or panels 11. The forward ends 52 of the folding fingers 51 are arranged to engage the under side of the back wall 15 and to swing it forwardly to the position shown in Figure 7. In order to accomplish this, the back end of each of the folding fingers 51 comprises a cam 53. As the folding fingers 51 are swung by the cables or chains 46 around the sprockets 47, the cams 53 engage collars 56 fastened thereto and, as a result, the fingers 51 are swung from a position at right angles to the cables or chains 46 in a counter-clockwise direction. This movement is illustrated by the broken line showing of one of the fingers 51 in Figure 2 as the cam 53 engages the collar 56 and moves the finger 51 so that the forward ends 52 engage the under side of the back wall or flap 15 and fold it over the bottom wall or panel 11.

The forward folding of the back wall or flap 15 is accomplished in part only by the engagement of the cams 53 with the collars 56. The folding operation is completed by the engagement of the cams 53 with a track 51 which extends between the conveyor belts 22 and 24 and underneath the path of forward movement of the bottom wall or panel 11 and also tangent to the periphery of the collar 56 of each of the sprockets 47.

For purposes of description, the flaps 12 may be considered as side flaps of the blank, and the flaps 13 and 15 may be considered as end flaps. In operation it will be understood that the blank 10 with the side walls or flaps 12 extending from the bottom wall or panel 11 is fed forwardly between the conveyor belts 22 and 24 to a position where the half twists 31 in the top conveyor belts 24 can engage the side walls or flaps 12 and fold

the same over the bottom wall or panel 11. As will be understood, from what has been said, suitable hold down and feed means (not shown) is provided for feeding the blanks forwardly between belts 22 and 24 as and for the purpose stated. The hold down and feed means may be any suitable known means such, for example, as that shown in the Staude et al. Patent No. 2,291,063. If the plate 34 is employed, it serves to hold the side walls or flaps 12 in their folded positions. The blank 10 is moved forwardly and the forward edge of the front wall or flap 13 engages the long arm 40 of the front wall folder or finger 35 and slides upwardly along the same until it engages the short arm 42. Thereafter the front wall or flap 13 is folded back as the leading edge 14 of the bottom wall or panel 11 continues to move forwardly. At the same time the front wall folder or finger 35 is swung in a clockwise direction as shown in Figure 4. This folds the front wall or flap 13 back over the bottom wall or panel 11. After the blank 10 has passed completely beyond the front wall folder or finger 35, it swings back under the influence of the coil tension spring 39 to the position shown in Figures 2 and 3 of the drawings. By directing the top conveyor belts 24 over the pulleys 27, 28, 29 and 30 it will be noted that sufficient space is provided for permitting the front wall folder or finger 35 to function and to swing or fold the front wall 13 over in the manner just described and for folding over the back wall 15.

A sufficient number of pairs of lugs 45 are provided on the cables or chains 46 so that there always will be a pair ready to be engaged by the leading edge 14 of the next blank 10. The uppermost run of the cables or chains 46 extends underneath the path of the bottom wall 11.

It will be understood that the pair of folding fingers 51 associated with the pair of lugs 45 engaged by the leading edge 14 of the blank 10 are spaced therefrom sufficiently far to permit the bottom wall or panel 11 to completely clear the same. The adjustment is such that the trailing edge 16 of the bottom wall or panel 11 is positioned just ahead of the pivot point of the folding fingers 51 and at the base of the curved forward end 52 of the same. Then, as the fingers 51 are swung in a counter-clockwise direction by engagement of their cam ends 53 with the collars 56, the curved forward ends 52 serve to fold the back wall 15 over the bottom wall or panel 11 while at the same time the blank 10 continues to be moved forwardly. This folding operation performed on the back wall or flap 15 is completed by engagement of the cam ends 53 with the track 57 and the entering of its ends between the conveyor belts 22 and 24.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In a machine for folding the front and back walls relative to the bottom wall of a paperboard blank as it passes unidirectionally therethrough to form ultimately a rectangular carton, in combination, conveyor means for moving the blank forwardly, a front wall folder in the path of the forward movement of the blank for folding its

front wall backwardly relative to the bottom wall as it is moved forwardly, an endless flexible cable, guide means directing said cable so that a portion thereof parallels the path of the bottom wall, a lug secured to said cable and arranged to be engaged by the leading edge of the bottom wall with the front wall folded back whereby said cable is moved in synchronism with the forward movement of the partially folded blank, a folding finger pivoted on said cable at a distance from said lug determined by the length of the bottom wall, and cam means cooperating with said folding finger to rock it forwardly as the trailing edge of the bottom wall passes thereby for folding the back wall forwardly relative to the bottom wall.

2. In a machine for folding the front and back walls relative to the bottom wall of a paperboard blank as it passes unidirectionally therethrough to form ultimately a rectangular carton, in combination, conveyor means for moving the blank forwardly, a front wall folder in the form of an L-shaped finger with the long side arranged to be engaged by the leading edge of the front wall which slides therealong until it engages the short side to fold it backwardly relative to the bottom wall as the blank moves forwardly, support means for said finger rockably mounting it to swing about an axis transverse and parallel to the movement of the blank whereby it can be swung out of the path of the blank as the same is moved forwardly, spring means biasing said finger against movement imparted thereto by the blank, an endless flexible cable, guide means directing said cable so that a portion thereof parallels the path of the bottom wall, a lug secured to said cable and arranged to be engaged by the leading edge of the bottom wall with the front wall folded back whereby said cable is moved in synchronism with the forward movement of the partially folded blank, a folding finger pivoted on said cable at a distance from said lug determined by the length of the bottom wall, and cam means cooperating with said folding finger to rock it forwardly as the trailing edge of the bottom wall passes thereby for folding the back wall forwardly relative to the bottom wall.

3. In a machine for folding the front and back walls relative to the bottom wall of a paperboard blank as it passes unidirectionally therethrough to form ultimately a rectangular carton, in combination, conveyor means for moving the blank forwardly, a front wall folder in the path of the forward movement of the blank for folding its front wall backwardly relative to the bottom wall as it is moved forwardly, an endless flexible cable, guide means directing said cable so that a portion thereof parallels the path of the bottom wall, a lug secured to said cable and arranged to be engaged by the leading edge of the bottom wall with the front wall folded back whereby said cable is moved in synchronism with the forward movement of the partially folded blank, a folding finger pivoted on said cable at a distance from said lug determined by the length of the bottom wall, the forward end of said folding finger being arranged to engage the back wall and the back end of said folding finger comprising a cam, and abutment means positioned in the path of said cam and engageable thereby to rock said folding finger forwardly as the trailing edge of the bottom wall passes it for folding the back wall forwardly relative to the bottom wall.

4. In a machine for folding the front and back walls relative to the bottom wall of a paperboard

blank as it passes unidirectionally therethrough to form ultimately a rectangular carton, in combination, conveyor means for moving the blank forwardly, a front wall folder in the form of an L-shaped finger with the long side arranged to be engaged by the leading edge of the front wall which slides therealong until it engages the short side to fold it backwardly relative to the bottom wall as the blank moves forwardly, support means for said finger rockably mounting it to swing about an axis transverse and parallel to the movement of the blank whereby it can be swung out of the path of the blank as the same is moved forwardly, spring means biasing said finger against movement imparted thereto by the blank, an endless flexible cable, guide means directing said cable so that a portion thereof parallels the path of the bottom wall, a lug secured to said cable and arranged to be engaged by the leading edge of the bottom wall with the front wall folded back whereby said cable is moved in synchronism with the forward movement of the partially folded blank, a folding finger pivoted on said cable at a distance from said lug determined by the length of the bottom wall, the forward end of said folding finger being arranged to engage the back wall and the back end of said folding finger comprising a cam, and abutment means positioned in the path of said cam and engageable thereby to rock said folding finger forwardly as the trailing edge of the bottom wall passes it for folding the back wall forwardly relative to the bottom wall.

5. In a machine for folding the side, front and back walls relative to the bottom wall of a paper-board blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side walls over the bottom wall, a front wall folder in the path of the forward movement of the blank for folding its front wall backwardly over the bottom wall as it is moved forwardly, an endless chain, front and rear sprockets over which said chain is trained so that a run thereof parallels the path of the bottom wall underneath the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, and cam means cooperating with said folding finger to rock it forwardly as the trailing edge of the bottom wall passes thereby for folding the back wall forwardly over the bottom wall.

6. In a machine for folding the side, front and back walls relative to the bottom wall of a paper-board blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side

walls over the bottom wall, a front wall folder in the path of the forward movement of the blank for folding its front wall backwardly over the bottom wall as it is moved forwardly, a plate angularly disposed above the path of the blank between said half twists in said top belts and said front wall folder for engaging the folded side walls to keep the same folded until the front wall is folded over their forward ends, an endless chain, front and rear sprockets over which said chain is trained so that a run thereof parallels the path of the bottom wall underneath the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, and cam means cooperating with said folding finger to rock it forwardly as the trailing edge of the bottom wall passes thereby for folding the back wall forwardly over the bottom wall.

7. In a machine for folding the side, front and back walls relative to the bottom wall of a paper-board blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side walls over the bottom wall, a front wall folder in the form of an L-shaped finger with the long side arranged to be engaged by the leading edge of the front wall which slides therealong until it engages the short side to fold it backwardly over the bottom wall as the blank moves forwardly, support means for said finger rockably mounting it between said top belts to swing about an axis transverse and parallel to the movement of the blank whereby it can be swung out of the path of the blank as the same is moved forwardly, spring means biasing said finger against movement imparted thereto by the blank, an endless chain, front and rear sprockets over which said chain is trained so that a run thereof parallels the path of the bottom wall underneath the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, and cam means cooperating with said folding finger to rock it forwardly as the trailing edge of the bottom wall passes thereby for folding the back wall forwardly over the bottom wall.

8. In a machine for folding the side, front and back walls relative to the bottom wall of a paper-board blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side

walls over the bottom wall, a front wall folder in the path of the forward movement of the blank for folding its front wall backwardly over the bottom wall as it is moved forwardly, an endless chain, front and rear sprockets over which said chain is trained so that a run thereof parallels the path of the bottom wall underneath the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, cam means cooperating with said folding finger to rock it forwardly as the trailing edge of the bottom wall passes thereby for folding the back wall forwardly over the bottom wall, and pulleys over which each of said top belts is trained to direct each of them away from and back toward said bottom belts to provide a space where the front and back walls can be folded as aforesaid.

9. In a machine for folding the side, front and back walls relative to the bottom wall of a paperboard blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side walls over the bottom wall, a front wall folder in the path of the forward movement of the blank for folding its front wall backwardly over the bottom wall as it is moved forwardly, an endless chain, front and rear sprockets over which said chain is trained so that a run thereof parallels the path of the bottom wall underneath the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, the forward end of said folding finger being arranged to engage the back wall and the back end of said folding finger comprising a cam, and abutment means positioned in the path of said cam and engageable thereby to rock said folding finger forwardly as the trailing edge of the bottom wall passes it for folding the back wall forwardly over the bottom wall.

10. In a machine for folding the side, front and back walls relative to the bottom wall of a paperboard blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side walls over the bottom wall, a front wall folder in the path of the forward movement of the blank for folding its front wall backwardly over the bottom wall as it is moved forwardly, an endless chain, front and rear sprockets over which said chain is trained so that a run thereof parallels the path of the bottom wall underneath

the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, the forward end of said folding finger being arranged to engage the back wall and the back end of said folding finger comprising a cam, and a circular flange on said rear sprocket positioned in the path of said cam and engageable thereby to rock said folding finger forwardly as the trailing edge of the bottom wall passes it for folding the back wall forwardly over the bottom wall.

11. In a machine for folding the side, front and back walls relative to the bottom wall of a paperboard blank as it passes unidirectionally therethrough to form ultimately a rectangular carton, in combination, a pair of bottom carrier belts for receiving the blank along the sides of the bottom wall, a pair of top carrier belts cooperating with said bottom belts to move the blank positioned therebetween forwardly, each of said top belts having a half twist therein as the blank enters between said bottom and top belts to fold the side walls over the bottom wall, a front wall folder in the path of the forward movement of the blank for folding its front wall backwardly over the bottom wall as it is moved forwardly, an endless chain, front and rear sprockets over which said chain is trained so that a run thereof parallels the path of the bottom wall underneath the same and between said bottom carrier belts, a lug secured to said chain and arranged to be engaged by the leading edge of the bottom wall with the front wall folded back whereby said chain is moved in synchronism with the forward movement of the partially folded blank, a folding finger pivoted on said chain at a distance from said lug determined by the length of the bottom wall, the forward end of said folding finger being arranged to engage the back wall and the back end of said folding finger comprising a cam, a circular flange on said rear sprocket positioned in the path of said cam and engageable thereby to rock said folding finger forwardly as the trailing edge of the bottom wall passes it for folding the back wall forwardly over the bottom wall, and a track tangent to said circular flange and engageable by said cam after it leaves the same for holding the back wall in the folded position as the blank is moved forwardly by said top and bottom belts.

12. The invention, as set forth in claim 5, wherein a plurality of sets of lugs and folding fingers are carried by the chain so spaced that the lug of the next set is advanced into position for engagement by the forward edge of the bottom wall of the next blank as a result of the engagement of the preceding lug by the preceding blank.

13. The invention, as set forth in claim 12, wherein two chains are employed each having a plurality of sets of lugs and folding fingers carried thereby and positioned so that the forward edge of the bottom wall of the blank engages simultaneously a lug on each chain and the corresponding folding fingers act simultaneously to fold over its back wall.

14. In a machine for folding blanks having a bottom panel and end flaps connected to said panel along fold lines, means for advancing the blanks along a rectilinear path of travel, means

11

for folding the leading end flap of the blank toward said panel in the travel of the blank, an endless belt having a run paralleling the path of travel of the blanks and driven thereby, abutments on said belt disposed to be contacted by the leading edges of the blanks for driving said belt in the advancement of said blanks, contact of the moving blanks with said abutments providing the sole means for driving said belt, and folding means comprising folding members carried by said belt disposed and adapted to fold the following end flap of the respective blanks toward the bottom panel thereof in the continued travel of said blank and the travel therewith of said belt.

15. In a machine for folding blanks having a bottom panel and side and end flaps connected to said panel along fold lines, means for advancing the blanks along a rectilineal path of travel and folding said side flaps and the leading end flap toward said panel, an endless belt having a run paralleling the path of travel of the blanks and driven thereby, abutments on said belt dis-

5

10

15

posed and adapted to receive and be contacted by the leading end portion of the blanks for driving said belt in the advancement of said blanks, contact of the moving blanks with said abutments providing the sole means for driving said belt, cam means, and folding fingers cooperating with said cam means disposed and adapted to fold the following end flap of the respective blanks toward the bottom panel thereof in the continued travel of said blank and the travel therewith of said belt.
